UNITED STATES PATENT OFFICE.

GEORGE W. SCHILLING, OF PHILADELPHIA, PENNSYLVANIA.

DEVICE FOR REMOVING ARTICLES FROM SHAFTS.

1,317,944.

Specification of Letters Patent.

Patented Oct. 7, 1919.

Application filed October 22, 1918. Serial No. 259,246.

To all whom it may concern:

Be it known that I, GEORGE W. SCHILLING, a citizen of the United States, residing at Philadelphia, in the county of Philadelphia and State of Pennsylvania, have invented certain new and useful Improvements in Devices for Removing Articles from Shafts, of which the following is a specification.

One object of my invention is to provide a device of comparatively simple construction which will efficiently operate to remove articles such as gear wheels, pulleys, collars, couplings or propellers from shafts.

Another object is to so construct my invention that it can be made comparatively small and durable and will be operative to loosen and remove articles such as above noted irrespective of their position on the shaft; that is to say it will remove an article which is close to the end of the shaft or remove an article which is within the length of the shaft and a comparatively great distance from the ends of the shaft. Thus by my invention it is possible for example to shift or loosen a gear wheel or pulley which is interposed between two other articles on the same shaft.

A still further object is to so construct my invention that it can be easily positioned and manipulated by one man and can also be used for removing articles from shafts irrespective of whether the shaft is mounted in its bearings or detached therefrom. In this connection it will be noted that my invention can be mounted on a work bench or the like for removing articles from detached shafts.

These objects, and other advantageous ends which will be described hereinafter, I attain in the following manner, reference being had to the accompanying drawings in which—

Figure 1 is a top plan view of my invention showing how it can be positioned to remove a three blade propeller from a shaft, said propeller being shown in dot-and-dash lines and near the end of the shaft,

Fig. 2 is a section taken on the line 2—2 of Fig. 1,

Fig. 3 is a section taken on the line 3—3 of Fig. 1,

Fig. 4 is a side elevation of one of a number of link levers which I preferably employ,

Fig. 5 is a top plan view of the link lever shown in Fig. 4,

Fig. 6 is a top plan view of my invention showing the same secured to a shaft within its length and operative to loosen a gear wheel attached to said shaft, and

Fig. 7 is a section taken on the line 7—7 of Fig. 6.

Referring to the drawings and particularly to Figs. 1 to 5 inclusive, 9 represents the head of my improved device which is made in two sections 10 and 11 joined together at 12 by bolts 13. This head has a central hole 14 which is screw threaded and part of the hole being formed in each of the sections 10 and 11. This hole is adapted to receive a screw threaded plug 15 which has a centering pin 16 projecting outwardly from one end.

The head 9 is also provided with a projecting collar 17, substantially one half of the collar being carried by each of the sections 10 and 11. This collar has set screws 18 arranged around its circumference, as clearly shown in Figs. 1 and 3, and can be used if desired to secure the plug 15 within the head 9 or, as will hereinafter be explained, these set screws can be used for another purpose when the device is desired for use in the capacity illustrated in Figs. 6 and 7.

The head 9 has three slots 19, 20, and 21 through which pass bolts 22. These bolts 22 are screw threaded at their opposite ends, said screw threading extending a considerable distance inwardly from said ends, as clearly illustrated in Fig. 1.

Offset link levers 23 are provided, each of said levers having a circular hole 24 adjacent one end and an elongated slot 25 adjacent the opposite end. Three of these levers are arranged to register or overlap each other; as clearly shown in Figs. 1 and 2, the slots 25 in the link levers 23 and the slots 19, 20 and

21 permitting adjustment radially of the bolts 22 to suit various requirements for different size shafts or for wheels, propellers or the like of different sizes.

5 Groups 26 and 27 of the link levers 23 are provided at opposite ends of the bolts 22, the group 27 engaging the surface 28 of the head 9, while the group 26 as illustrated is in engagement with the blades of a propeller 29 and encircle the shaft 30 upon which the propeller is secured.

10 The center pin 16 is adapted to enter the centering recess 31 which is usually present in all shafts either for the purpose of taking 15 count of the revolutions of the shaft or for the reason that the recess was formed when the shaft was being turned in the lathe.

15 Nuts 32 and 33 are provided on the opposite ends of the bolts 22 and by turning these 20 bolts the group 26 of link levers 23 will move toward the head 9 and in so doing will slide 25 toward the propeller 29 toward the adjacent end of the shaft 30. In this manner the propeller can be quickly and easily removed from the shaft. Each of the offset link levers 23 is 30 provided with a recess 34 so that when the levers of these groups are in position such for example as shown in the group 26, they will encircle and provide room for the shaft 35 to pass therethrough; this arrangement being shown in assembly in Fig. 2.

35 If it is desired to remove or loosen an article located within the length of the shaft, for example between two other articles, the head 9 can be clamped directly to the shaft by removing the bolts 13 and separating the sections 10 and 11. The head thus separated can be placed at the desired position on the shaft and after thus positioned the bolts 13 40 can again be inserted and tightened; it being of course noted that the plug 15 has previously been removed. The set screws 18 can then be used to secure the head to the shaft, as clearly shown in Fig. 7. The bolts 22 45 can then be inserted through the slots 19 and the levers 23 can be arranged in the groups 26 and 27. The article to be removed, such for example as the gear wheel 35, being positioned between the group 26 of levers 50 and the head 9 can, by turning the nuts 32 and 33, be slid longitudinally of its shaft to free its key 36.

55 The head 9 is provided with feet 37 so that it can be stood upon a work bench and these feet 37 are provided with holes 38 so that if desired the head can be bolted to a bench or any other object desired.

60 The offset formation of the link levers 23 provides a strong interlock so that the groups have their opposite faces substantially flush so as to evenly engage the side surfaces of gear wheels, pulleys, propellers or the like and as clearly evident from the several views of drawing.

65 Furthermore, by having the head 9 provided with the set screws 18 it is an easy matter to quickly clamp the head to a shaft and the hands of the workman are free to manipulate the bolts 22, link levers 23 and nuts 32 and 33.

70 While I have described my invention as taking a particular form, it will be understood that the various parts of my invention may be changed without departing from the spirit thereof, and hence I do not 75 limit myself to the precise construction set forth, but consider that I am at liberty to make such changes and alterations as fairly come within the scope of the appended claims.

80 Having thus described my invention, what I claim as new and desired to secure by Letters Patent is:

1. A device of the character described including a head adapted to be supported on a shaft; bolts extending through said head; and a group of levers connected together and through which said bolts extend, said bolts having nuts thereon whereby when the nuts are tightened said levers are moved 90 toward said head, substantially as described.

2. A device of the character described including a head adapted to be supported on a shaft; bolts extending through said head; and groups of levers connected together and positioned at opposite sides of said head and having openings through which said bolts extend, said bolts having nuts thereon whereby when the nuts are tightened said groups of levers are moved toward each 100 other, substantially as described.

3. A device of the character described including a head adapted to be supported on a shaft; bolts extending through said head; and a group of offset levers having overlapping portions provided with registering openings, said bolts extending through said registering openings in said levers, said bolts having nuts thereon whereby when the nuts are tightened said levers are moved 110 toward said head, substantially as described.

4. A device of the character described including a head made in transversely adjustable sections and having a hole formed jointly in said sections so that a portion of a 115 shaft can be confined within said hole by separating the sections and then moving them together in a direction transversely of the axis of the shaft; means for securing the head to said shaft; and power transmitting 120 means supported by said head and adapted to move an article longitudinally of said shaft, substantially as described.

5. A device of the character described including a head having a screw threaded hole 125 formed therein; a screw threaded plug fitting said screw threaded hole and having a portion for engagement with an end of a

- shaft; bolts supported by said head; and a group of overlapping levers mounted on said bolts, said bolts having nuts thereon adapted to move said group of levers toward 5 said head, substantially as described.
6. A device of the character described including a head having a hole therein; a plug secured within said hole and having a portion for engagement with an end of a 10 shaft; bolts supported by said head; and a group of overlapping levers mounted on said bolts, said bolts having nuts thereon adapted to move said group of levers toward 15 said head, substantially as described.
- 15 7. A device of the character described including a head made in sections and having a screw threaded hole formed jointly in said sections; a screw threaded plug fitting said screw threaded hole and having a portion 20 for engagement with an end of a shaft; bolts supported by said head; and a group of overlapping levers mounted on said bolts, said bolts having nuts thereon adapted to move said group of levers toward 25 said head, substantially as described.
8. A device of the character described including a head made in sections and having a hole formed jointly in said sections; a plug secured within said hole and having 30 a portion for engagement with an end of a shaft; bolts supported by said head; and a group of overlapping levers mounted on said bolts, said bolts having nuts thereon adapted to move said group of levers to 35 ward said head, substantially as described.
9. A device of the character described including a head made in transversely adjustable sections and having a hole formed jointly in said sections so that a portion of 40 a shaft can be confined within said hole by separating the sections and then moving them together in a direction transversely of the axis of the shaft; means for securing said sections together, said screws on said
- head leading into said hole and adapted to 45 engage said shaft; and power transmitting means supported by said head and adapted to move an article transversely of said shaft, substantially as described.
10. A device of the character described including a head adapted to be supported on a shaft, said head having slots therein extending in a substantially radial direction; bolts extending through said slots; and a group of overlapping levers having register- 55 ing openings therein, certain of which are in the form of slots, said bolts respectively extending through said registering openings, said bolts having nuts thereon whereby when the nuts are tightened said levers are 60 moved toward said head, said slots in the levers and head permitting adjustment of said bolts toward or from each other, substantially as described.
11. A device of the character described 65 including a head adapted to be supported on a shaft, said head having slots therein extending in a substantially radial direction; bolts extending through said slots; and groups of overlapping levers at opposite 70 sides of said head, the levers of each of said groups having registering openings therein, certain of which are in the form of slots, said bolts respectively extending through said registering openings, said bolts having 75 nuts thereon whereby when the nuts are tightened said levers are moved toward said head, said slots in the levers and head permitting adjustment of said bolts toward or from each other, substantially as described. 80
- In testimony whereof I have signed my name to this specification in the presence of two subscribing witnesses.
